By G. A. Gross, Atty.

UNITED STATES PATENT OFFICE.

JOHN H. NELSON, OF CHICAGO, ILLINOIS, ASSIGNOR TO HARRY A. DOUGLAS, OF BRONSON, MICHIGAN.

ELECTRIC SWITCH.

Application filed February 18, 1927. Serial No. 169,348.

My invention relates to electric switches and has for one of its objects the provision of an improved form of switch contacting structure and for another of its objects the provision of a current conducting winding element so associated with the switch as to reduce the aggregate length of the winding element and switch and make the combination of the winding element and switch more compact.

A switch structure realizing the first object of my invention comprises two spaced apart electric current conducting contacts placed abreast, a connector containing two electrically connected contacts, and a spring pressing these contacts outwardly from each other, said connector being mounted to move to bring its contacts into engagement with the first aforesaid contacts and out of connection therewith. In the preferred embodiment of the invention, the connector is mounted to turn and is disposed in the zone of the first contacts and the contacts of the connector are in telescoping relation, there being a spring pressing these contacts outwardly from each other so as to be engageable with the first aforesaid contacts to close the circuit that is provided therewith.

A switch structure realizing the second object of my invention comprises an electric current conducting winding tubular in form, spaced apart electric current conducting contacts placed abreast on opposite sides of the bore of said winding, and a connector in the zone of said contacts and mounted to turn into engagement with the aforesaid contacts and out of connection therewith. In the preferred embodiment of this feature of my invention, the connector is mounted to turn and is inclusive of the two electrically connected contacts in telescoping relation and the spring pressing these contacts outwardly from each other. A locking structure is desirably provided for controlling the position of said connector, this locking structure being preferably key operated and, as I have employed the invention, serving to hold the connector in circuit opening adjustment, though the invention is not to be thus limited.

I will explain my invention more fully by reference to the accompanying drawings in which Fig. 1 illustrates a winding element in longitudinal section and the structure of the switch partially in section and partially

in elevation; Fig. 2 is a front view of a part of the structure shown in Fig. 1; Fig. 3 is a sectional view on line 3-3 of Fig. 1; Fig. 4 is a sectional view on line 4-4 of Fig. 1; Fig. 5 is a sectional view on line 5-5 of Fig. 1; Fig. 6 is a sectional view on line 6-6 of Fig. 1; Fig. 7 is an end view of a container for the switching mechanism and of a carrier for the contacts of a connector; Fig. 8 is an end view of the locking structure which has an element, a tumbler barrel, shaped to engage said carrier whereby the carrier may be turned to turn the connector; Fig. 9 is a sectional view on line 9-9 of Fig. 1; Fig. 10 is a perspective view showing the connector, the contact structure engageable by the connector, and the locking structure in separated relation; Fig. 11 is a perspective view illustrating the disposition of the container shown in Fig. 7; and Fig. 12 is a diagram illustrating the use of my invention in connection with the ignition system of an internal combustion engine.

The hollow current conducting element 80 illustrated is inclusive of a winding 1 constituting the primary of an induction coil that is employed in a circuit serving to produce sparks in the cylinders of an internal combustion engine. Another winding 2 is 85 illustrated which, in this instance, is secondary to the winding 1, this secondary winding being shown as being surrounded by the primary winding. The primary winding has one terminal grounded through a circuit interrupter 3 whose contacts are shunted by a condenser 4. The other terminal of the primary winding is grounded through a battery 6. The secondary winding 2 also has one terminal grounded through the circuit 90 interrupter 3, the other terminal of the winding 2 being connected with the revolving arm 7 of a distributor whose waiting contacts 8 are successively engaged by said arm, these waiting contacts being connected with the electrodes 9 of spark plugs or other 95 gas igniting elements that are contained in the various cylinders of the internal combustion engine, indicated at 10, that is equipped with the ignition system.

The windings 1 and 2 are tubular, the bore of the inner winding having a cylindrical lining 11 of insulation. A magnetizable core 12 is shown disposed within said lining, this core extending to one end of the winding 100 105 110

structure and terminating short of the other end of the winding structure to permit the switching mechanism to be received within the bore of the winding 2, as will hereinafter more fully appear. The winding 1 is surrounded by a jacket 13 of insulation. The two windings are faced at their ends by rings of insulation 14 and 15 which are inwardly turned at their peripheries to constitute annular flanges 14', 15' which surround and closely engage the jacket 13. A metallic jacket encases the winding structure, this metallic jacket having one cup shaped portion 16 and another cup shaped portion 17, the skirts of these cup shaped portions being in lapping relation, as indicated at 18. The cup shaped portion 17 has a reduced forwardly extending continuation 19, the front end wall of the cup portion 19 being clamped between a ring 20 and the mounting panel 21 by means of the clamping screws 22. A locking guard, preferably in the form of a shell 23, is carried by the front end wall of the portion 19 and projects inwardly, the inner end of the shell 23 being in the zone of the ring 15. A tumbler barrel 24 is mounted to turn in the shell 23, this tumbler barrel carrying tumblers 25 which are receivable at their ends in slots 26 formed in opposite sides of the shell 23. These tumblers are operable by a key 27, that is acceptable by the tumbler barrel, to be withdrawn from said slots when the key is inserted. When the tumblers are thus withdrawn, the tumbler barrel may be turned to a position in which the circuit of the coil 1 is either opened or closed, as will more fully appear. When the circuit is opened, the key may be withdrawn to permit the tumblers to enter said slots, the tumblers then serving to lock the primary circuit in open adjustment, as will also more fully appear.

The switching mechanism includes a carrier 28, made of insulation, which has a slot formation 29 shaped correspondingly to the oblong inner end 24' of the tumbler barrel received in the slot whereby this carrier may be turned when the tumbler barrel is turned. The carrier 28 is formed with a reduced inner end 30 that is receivable within the cylindrical recess that is formed in the container 31 that is made of insulating material, this container being receivable within the container 32. As shown, the container 32 is in the form of a shell which is square in cross section, the container 31 being correspondingly shaped and snugly received in said container 32. Two spaced apart electric current conducting contacts 33 and 34 serially included in the primary circuit are located abreast and are carried by the container 31, these contacts being of arcuate formation and having their inner faces curved to coincide with the circle of the cy-

lindrical recess in container 31, these contacts, said recess and the carrier 28 being coaxial. The extension 30 of the carrier 28 is formed with an opening 35 extending diametrically therethrough, this opening receiving the connector which is employed to connect the contacts 33 and 34 when the primary circuit is to be closed. This connector is preferably inclusive of two hollow cup shaped electrically connected contacts 36 and 37 that are in telescoping or sliding relation. A metallic coiled spring 38 is surrounded by the contacts 36 and 37 and presses these contacts outwardly from each other so that they engage the cylindrical surface of the recess in the container 31 or the inner faces of the contacts 33 and 34, according to the position to which the carrier 28 is turned. The connector 36, 37, 38 is thus disposed in the zone of said contacts 33, 34 and turns in this zone to circuit opening or circuit closing position, according to the position to which the carrier 28 is turned. The wire leading from the contact 33 to the primary winding and the wire leading from the contact 34 to the circuit interrupter are continued through a passage 39 that is formed in the core 12. The contacts 36, 37 of the connector move transversely to the axis of the windings instead of along this axis, thereby reducing the axial length of the structure and permitting such a disposition of the contacts 33 and 34 as further to reduce the axial length of the structure.

The inner end of the locking structure is snugly received within the front end of the lining 11 to guard the switch from unwarranted access. The switch is further guarded by means of the larger, outer end of the carrier 28.

The pair of contacts 33 and 34 and the connector 36, 37, 38 are relatively rotatable, and either said pair of contacts or said connector may be turned with respect to a point in space, and the claims are drawn with this understanding.

Changes may be made without departing from the invention.

Having thus described my invention, I claim:

1. The combination with an electric current conducting winding tubular in form; spaced apart electric current conducting contacts placed abreast on opposite sides of the bore of said winding; a connector in the zone of said contacts and comprising two electrically connected contacts in telescoping relation and a spring pressing these contacts outwardly from each other, said connector being adapted to turn with respect to and into engagement with the aforesaid contacts and out of connection therewith; and a locking structure in controlling relation to said connector.

2. The combination with an electric cur-

rent conducting winding tubular in form; spaced apart electric current conducting contacts placed abreast on opposite sides of the bore of said winding; a connector in 5 the zone of said contacts and comprising two electrically connected contacts and a spring pressing these contacts outwardly from each other, said connector being adapted to turn with respect to and into 10 engagement with the aforesaid contacts and out of connection therewith; and a locking structure in controlling relation to said connectors.

3. The combination with an electric current 15 conducting winding tubular in form; spaced apart electric current conducting contacts placed abreast on opposite sides of the bore of said winding; and a connector in the zone of said contacts and comprising 20 two electrically connected contacts and a spring pressing these contacts outwardly from each other, said connector being adapted to turn with respect to and into engagement with the aforesaid contacts and out of 25 connection therewith.

4. The combination with an electric current 30 conducting winding tubular in form; spaced apart electric current conducting contacts placed abreast on opposite sides of the bore of said winding; and a connector in the zone of said contacts and comprising 35 two electrically connected contacts in telescoping relation and a spring pressing these contacts outwardly from each other, said connector being adapted to turn with respect to and into engagement with the aforesaid contacts and out of connection therewith.

5. In an electric switch, the combination 40 with two spaced apart electric current conducting contacts placed abreast; of a connector comprising two electrically connected

contacts and a spring pressing these contacts outwardly from each other, said connector being movable with respect to said 45 contacts to bring its contacts into engagement with the first aforesaid contacts and out of connection therewith.

6. In an electric switch, the combination 50 with two spaced apart electric current conducting contacts placed abreast; of a connector disposed in the zone of said contacts and comprising two electrically connected contacts and a spring pressing these contacts outwardly from each other, said connector being rotatable with respect to said 55 contacts to bring its contacts into engagement with the first aforesaid contacts and out of connection therewith.

7. In an electric switch, the combination 60 with two spaced apart electric current conducting contacts placed abreast; of a connector comprising two electrically connected 65 contacts in telescoping relation and a spring pressing these contacts outwardly from each other, said connector being movable with respect to said contacts to bring 70 its contacts into engagement with the first aforesaid contacts and out of connection therewith.

8. In an electric switch, the combination 75 with two spaced apart electric current conducting contacts placed abreast; of a connector disposed in the zone of said contacts and comprising two electrically connected contacts in telescoping relation and a spring 80 pressing these contacts outwardly from each other, said connector being rotatable with respect to said contacts to bring its contacts into engagement with the first aforesaid contacts and out of connection therewith.

In witness whereof, I hereunto subscribe my name,

JOHN H. NELSON.
